UNITED STATES PATENT OFFICE.

COLVILLE B. SISSON, OF PROVIDENCE, RHODE ISLAND.

DESIGN FOR A TOY OR SIMILAR ARTICLE.

60,741.

Specification for Design. Patented Mar. 28, 1922.

Application filed September 14, 1921. Serial No. 500,694. Term of patent 14 years.

To all whom it may concern:

Be it known that I, COLVILLE B. SISSON, a citizen of the United States, residing at Providence, in the county of Providence and State of Rhode Island, have invented a certain new, original, and ornamental Design for a Toy or Similar Article, of which the following is a specification.

In the accompanying drawings which form a part of this specification,

Figures 1 and 2 are a side view and a front view respectively of a sign or toy embodying my design.

I claim:

The ornamental design for a toy or similar article, as shown.

COLVILLE B. SISSON.
